UNITED STATES PATENT OFFICE.

WLADYSLAW LOSIN, OF NIAGARA FALLS, NEW YORK.

WINGED PROJECTILE.

1,294,924.

Specification of Letters Patent.

Patented Feb. 18, 1919.

Application filed October 12, 1918. Serial No. 257,847.

To all whom it may concern:

Be it known that I, WLADYSLAW LOSIN, a citizen of Russia, residing at Niagara Falls, county of Niagara, and State of New York, have invented certain new and useful Improvements in Winged Projectiles, of which the following is a specification.

This invention relates to improvements in projectiles and particularly those which carry an explosive charge.

The principal object of the invention is to provide a projectile which will travel an unusually great distance and to combine means therewith which materially augment its flight, and maintain its aim and accuracy.

These and other like objects are attained by the novel construction and combination of parts hereinafter described and shown in the accompanying drawings, forming a material part of this disclosure, and in which:—

Figure 1 is a top plan view showing a projectile made in accordance with the invention, the wings being extended.

Fig. 2 is a similar view of the same, parts being broken away in order to disclose the interior construction.

Fig. 3 is a transverse sectional view taken on line 3—3 of Fig. 2, and,

Fig. 4 is an enlarged transverse sectional view taken through the forward part of the projectile, the wings being shown in a folded position.

Referring to the drawings, the projectile will be seen to consist of a cylindrical body 10, having a conical front end 11, terminating in a hard point 12.

Formed adjacent to the base of the cone 1, at opposite points within the body are internal projections 14, extending into the hollow body 15, which is adapted to contain high explosive, detonated either by a fuse or by percussion as the projectile strikes a solid object. Formed in the projections 14 are open recesses 16, adapted to contain wing-like elements 18, the same being closely fitted, as shown in Fig. 4, prior to the discharge of the projectile, the inner edge of the wing 18 being secured within the recesses 16, so as to prevent their complete separation from the body of the projectile, while the outer front edges are stiffened by extending

arms 19, which are normally projected laterally outward by coiled compression springs 20 secured in the bottom of the recesses, and 55 pressing against the arms 19 as shown best in Fig. 2, the arms normally folded along the lines 21 when in a closed position.

Also formed internally of the body 10, and extending inward from its rear end, is a cylindrical extension 22, having an open rectangular recess 23, at its center, provided upon two of its opposite sides with slots 24, which extend from the bottom 25, to a point 26 near the rear outer end of the body. 65

Slidably engaged in the slots are the ends of a bar 28, formed with a stem 29, the bar being substantially T shaped, and engaged with the outer end of the stems is a short transverse bar 30, having arms 31, pivoted 70 at its extremities, the arms 31, having extending between them a fan shaped tail or wing element 32, made of textile fabric like that of the wings 18, and adapted to be folded and pressed within the recess 23, this 75 element being expanded when extended by the spring 33, exerting pressure between the arms 31 at their lower ends adjacent to the bar 30.

In operation, the fan tail 32, having been 80 pressed within the recess 23, and the wings 18 folded within the recesses 16, the projectile is in condition to be discharged it being presumed that it has already been loaded with a supply of high explosive; immediately upon leaving the muzzle of the gun the springs 20 operate and force the wings 18 due to their relative inertia outwardly, the tail fan 32 being forced out, due to the movement of the projectile, these three elements 85 tending materially to support the projectile upon its course, and also assist in maintaining it in moving in a straight line.

Having thus described my invention what I claim as new and desire to secure by Letters Patent, is:—

In a winged projectile, the combination with a cylindrical body having a conical point and adapted to contain a charge of explosive, of open recesses formed upon opposite sides of said body, flexible winged elements normally contained in said recesses, means for stiffening the outer edge of said winged elements, means for projecting said

winged elements outward upon the release of said body, a rectangular recess extending inward from the rear of said body, slide-ways formed in said recess, a guide movable in said slide-ways, a bar extending from said guide, a pair of arms pivoted to said bar, flexible fabric extending between said

arms, and means for spreading said arms thereby forming a third wing at the rear of said body.

In testimony whereof I have affixed my signature.

WLADYSLAW LOSIN.
